FURRING SUPPORT FOR CONCRETE
STRUCTURESLouis F. Sylvester, Teaneck, N. J., assignor of
one-half to Max Platt, Bayonne, N. J.

Application May 2, 1933, Serial No. 668,937

11 Claims. (Cl. 72—118)

This invention relates to an improved means for furring in connection with cast concrete structures of various kinds; and the invention has reference, more particularly, to a novel supporting hanger adapted to be molded into and bonded to the concrete mass when the latter is cast.

This invention has for its principal object to provide a simple and effective type of hanger for supporting furring in connection with concrete structures; the same being of such form as to be capable of rapid and easy initial attachment to the forms in which the concrete is cast, whereby, upon removal of the forms, the hangers will be firmly and securely imbedded and anchored in the concrete mass, and will, when so affixed to the latter, provide freely projecting hanger arms through which furring material, such as rods, channels, etc., may be snaked or threaded so as to be supported along exterior surfaces of the concrete ready for use in attaching thereto ceilings, lintels, slabs or other superimposed structures.

Another object of this invention is to provide a novel type of furring support or hanger adapted to be initially mounted in connection with concrete casting forms preparatory to pouring the concrete; the support or hanger having a gauging or stop portion to coact with the forms so as to uniformly predetermine the projection of the hanger arm from the cast concrete mass.

Another object of this invention is to provide a type of furring support or hanger which, as initially attached to the casting form, is stabilized and firmly secured and supported against accidental displacement pending the casting of concrete in the form.

Another object of the invention is to provide a furring support or hanger so devised and arranged and so related to the casting forms that, when the casting forms are removed, the hangers will be ready for the reception of furring without necessity of make-ready operations to bring the same into final operative positions preparatory to attaching the furring material thereto.

A further object of this invention is to provide a furring support or hanger for the purposes described, but which also affords means for supporting and positioning concrete reenforcing rods in desired spaced relation to the sides and bottom of floor beam portions of a concrete floor structure preparatory to casting thereof.

Other objects of this invention, not at this time more particularly enumerated, will be understood from the following detailed description of the same.

Illustrative embodiments of this invention are shown in the accompanying drawings, in which:

Fig. 1 shows a sectional view of a cast concrete building floor having integral beam portions as cast in the forms for molding the same, and showing the novel furring supports or hangers of this invention as initially attached to and supported by the form so as to be operatively molded into and anchored in the concrete mass cast into the forms.

Fig. 2 is a similar sectional view, showing the forms removed from the concrete structure, and the furring material as supported by the novel hangers of this invention, to, in turn, operatively support a ceiling structure.

Fig. 3 is a fragmentary sectional view, taken on line 3—3 in Fig. 2; and Fig. 4 is a fragmentary sectional view, on an enlarged scale, taken on line 4—4 in Fig. 1.

Fig. 5 is a perspective view of one form of the novel furring support or hanger; and Fig. 6 is a perspective view of a modified form of the novel furring support or hanger.

Fig. 7 is a fragmentary view, in part section, showing the novel furring support or hanger adapted to receive channel type furring material; and Fig. 8 is a view in elevation, looking from left to right in Fig. 7.

Fig. 9 is a fragmentary sectional view of a concrete beam portion of a floor structure and part of the forms therefor, but showing in side elevation a modified form of furring support or hanger adapted to also serve as a support for positioning concrete reenforcing rods preparatory to casting said floor structure; and Fig. 10 is a perspective view of said modified form of furring support or hanger.

Similar characters of reference are employed in the above described views, to indicate corresponding parts.

Referring to the drawings, the preferred form of furring support or hanger is shown in Fig. 5; the same being made of a metallic strip or strap of suitable width and thickness, as e. g. a width of approximately one inch, and a thickness of approximately from one-sixteenth to one-eighth of an inch, although it will be understood that these measurements are not critical, but are suggested as adequate for the average conditions of use. If massive structures are to be erected, the size and proportions of the hanger devices may be increased; and, on the other hand, for light structures, the size and proportions of the hanger devices may be reduced. The novel

hanger device comprises a base or foot portion 10. Formed at the outer end of said base or foot portion 10 is an upwardly extending anchor-loop 11 of an inverted substantially U-shape. 5 The outer leg of said anchor-loop 11 is extended downwardly for a substantial distance below the plane of said base or foot portion 10, to provide a depending hanger arm 12. Struck from said hanger arm 12 is an up-turned inwardly projecting gauging or stop lug 13, disposed to project substantially at right angles thereto and to lie in the plane of said base or foot portion 10. The removal of said gauging or stop lug 13 from the body of said hanger arm 12 provides the latter 10 with an opening or eye 14 adapted in use to receive and support a furring rod or the like. Formed in the base or foot portion 10, so as to be laterally off-set from a line extending through the center of said opening or eye 14 is a nail hole 15.

Referring now to Fig. 1 of the drawings, there is shown therein an arrangement of forms for casting a building floor 16 having integral beam portions 17 depending from its under side, in connection with which are arranged the novel furring supports or hangers of this invention, whereby the use of the latter is illustrated. These casting forms comprise girder timbers 18 aligned substantially centrally of the desired locations 25 of the beam portions 17. Supported by and upon said girder timbers 18 are the beam bottom floor boards 19. Secured to the side faces of said girder timbers 18 are ledge pieces 20, upon which are supported, to extend between said girder timbers 18, bridge boards 21 which are adapted to support the metal arch pans 22, whereby the latter are operatively disposed to define the sides 30 of the beam portions 17 and the floor bottom arches 23 extending therebetween. Fixed on said bridge boards 21 are positioning battens 24 to engage and retain the arch pans 22 against accidental lateral displacement or shifting pending the casting of concrete into the form.

After the timbering and beam bottom boards 45 of the casting forms have been erected, and prior to the insertion of the arch pans 22 and their supports to complete the forms, the hanger devices of this invention are mounted upon and temporarily attached to the beam bottom floor 50 boards 19. In so mounting the hanger devices, each of the same are disposed with their base or foot portions 10 footed upon the upper surface of the beam bottom floor boards 19, with their anchor-loops 11 toward the margins of the latter, 55 and with their hanger arms 12 extending downwardly over the edges of said boards 19, but having their gauging or stop lugs 13 abutting the upper surfaces of said boards 19. The hanger devices may be mounted in spaced apart relation 60 according to the desired distance of spacing desired as to the furring material to be installed. To retain the hanger devices in place nails 25 are drawn downwardly through the nail holes 15 thereof into the boards 19. When the hanger 65 devices are mounted in the manner described, the same are firmly footed upon the boards 19, and by reason of the engagement of the latter by the gauging or stop lugs 13, the same are not only firmly braced against downward tipping or other 70 displacement, but the extent of downward projection of the hanger arms 12 is predetermined and is maintained uniform in relation one to another so that the furring rod receiving openings or eyes 14 thereof are operatively aligned from one beam to another ready for the insertion 75

therethrough of the furring rods. It will be understood that the hanger devices may be mounted along either one or both margins of the boards 19, as may be deemed desirable.

Upon setting of the hanger devices and completion of the forms, the concrete is cast into the latter to mold the building floor 16 and its integral beam portions 17. As the fluid concrete is cast into the forms, the same flows downwardly over the base or foot portions 10 of the hanger devices and into and around the bights of the anchor-loops 11 thereof, so that, when the concrete hardens, the latter will be firmly imbedded and anchored in the concrete mass, so as to hold the hanger devices immovable.

Upon removing the arch pans 22 and their supports, the girder timbers 18 may be removed, and then the beam bottom floor boards 19 may be stripped away from the beam portions 17, whereupon the hanger arms 12 of the hanger devices 85 will be exposed in operative depending extension from the finished beam portions 17.

After removal of the forms, furring rods 26 are snaked or threaded through the openings or eyes 14 of the exposed hanger arms 12 so as to be supported thereby for extension in desired spaced apart relation beneath and across the bottom faces of the beam portions 17. To the furring rods 26, as thus supported across the under side of the floor structure, metallic ceiling 28 is applied in the usual manner.

Referring to Fig. 6 of the drawings, I have shown therein a hanger device of somewhat modified shape, wherein the anchor-loop 11', which extends from the forward end of the base or foot portion 10', is of regular shape, with its front leg perpendicular and its rear leg inclined. This shape is better adapted for use in connection with floor beam portions in which reenforcing rods are employed, since it better permits the latter to be disposed adjacent to the sides and bottom of said floor beam portions. The gauging or stop lug 13', shown in connection with the hanger arm 12' of this modified form of hanger device, is of substantially circular form to provide a round eye 14', if such form is desired.

Referring to Figs. 7 and 8 of the drawings, I have shown therein, a modified form of hanger device having in its hanger arm 12 an opening or eye 14 enlarged to accommodate furring 29 of the channel bar type.

It will be understood with respect to the various forms of hanger devices that the length of the hanger arm 12 may be increased if it is desired to more distantly space the lath and plaster 130 from the under side of the floor structure; in which case the openings or eyes 14 are located accordingly.

Referring to Figs. 9 and 10 of the drawings, I have shown another modification of the novel 135 hanger device which serves the additional function of supporting concrete reenforcing rods preparatory to casting the concrete structure. This form of hanger device comprises an anchor loop in the form of a raised main body or bridge-piece 140 30 having at its inner end a downwardly projecting leg or foot-piece 31 and at its outer end a downwardly projecting leg 32 terminating in a hanger arm 33. Struck or bent from said hanger arm 33 is an upturned inwardly projecting gauging or stop lug 34 disposed to lie substantially in the plane of the free end of said leg or foot-piece 31. The displacement of said gauging or stop lug 34 from the body of said hanger arm 33 provides the latter with an opening or eye 35 adapted 150

- in use to receive and support a furring rod or the like. Formed in the body or bridge-piece 30, so as to be laterally off-set from a line extending through the center of said opening or eye 35 is a nail hole 36. Struck into upstanding relation to the body or bridge piece 30, preferably from opposite sides thereof, so as to be spaced apart a desired distance longitudinally of said body or bridge are rod-rest lugs 37, the upper free ends of the same being preferably somewhat indented or notched as at 38. This combined hanger device and reenforcing rod support is used as follows:
- When the girder timbers 18 and the beam bottom floor boards 19 are set up, the hanger devices are mounted and temporarily attached to the latter in spaced apart relation along the same. Each hanger device is set transversely of the floor board 19 so as to extend across almost the full distance of the width of beam to be cast. As so disposed, the leg or foot-piece 31 rests upon the floor board 19 adjacent to one margin thereof, while the opposite leg 32 is positioned to dispose the hanger arm 33, extending therefrom, downwardly over the opposite margin of the floor board 19, with the gauging or stop lug 34 abutting the upper surface of said floor board, thereby spacing the body or bridge-piece 30 above and substantially parallel to the floor board so as to form an anchor-loop portion adapted to be imbedded in the concrete mass of the beam, when the latter is cast. To hold the device in place preparatory to casting the concrete, a fastening nail 39 is driven downwardly through the nail hole 36 and into the floor board 19.
- When the hanger devices are thus mounted, reenforcing rods 40 may be mounted across the same upon the rod-rest lugs 37, as shown in Fig. 9, thus supporting said rods 40 in properly spaced relation to the sides and bottom of the beam preparatory to the casting thereof, and so as to be imbedded in said beam when it is cast. Upon removal of the form material after the floor structure and its beam portions are cast, the body of the hanger device will be firmly imbedded and anchored in the mass of the concrete, while the hanger arm 33 will project downwardly and exteriorly from the latter, ready to receive and support the furring material substantially in the manner as already above described.
- I claim:—
1. A furring hanger device adapted to be mounted in connection with a concrete casting form so as to be anchored in a concrete structure when poured thereinto, comprising an upwardly arched anchor-loop portion to be initially footed upon a form wall, a perforate hanger arm depending from one end of said anchor-loop portion to project exteriorly of the form, and a gauging stop portion projecting angularly from said hanger arm to engage with the form wall so as to both support said anchor loop against displacement and predetermine the distance of extension of said hanger arm from the cast concrete structure.
  2. A furring hanger device adapted to be mounted in connection with a concrete casting form so as to be anchored in a concrete structure when poured thereinto, comprising an upwardly arched anchor-loop portion to be initially footed upon a form wall, a perforate hanger arm depending from one end of said anchor-loop portion to project exteriorly of the form, a gauging stop portion projecting angularly from said hanger arm to engage with the form wall so as to both support said anchor loop against displacement and predetermine the distance of extension of said hanger arm from the cast concrete structure,
- ment and predetermine the distance of extension of said hanger arm from the cast concrete structure, and said anchor-loop portion having means to support and position reenforcing rods within the form preparatory to casting the concrete
3. A furring hanger device adapted to be mounted in connection with a concrete casting form so as to be anchored in a concrete structure when poured thereinto, comprising a unitary member produced from a metallic strip, comprising an upwardly arched anchor-loop having an inner leg portion to be footed upon a form wall, a perforate hanger arm extending downwardly from the other leg portion of said anchor-loop to project exteriorly from the form, and a gauging stop lug struck out of said hanger arm inwardly thereof and adapted to engage with the form wall so as to both support said anchor-loop against displacement and predetermine the distance of extension of said hanger arm from the cast concrete structure.
4. A furring hanger device adapted to be mounted in connection with a concrete casting form so as to be anchored in a concrete structure when poured thereinto, comprising a unitary member produced from a metallic strip, comprising an upwardly arched anchor-loop having an inner leg portion to be footed upon a form wall, a perforate hanger arm extending downwardly from the other leg portion of said anchor-loop to project exteriorly from the form, a gauging stop lug struck out of said hanger arm inwardly thereof and adapted to engage with the form wall so as to both support said anchor-loop against displacement and predetermine the distance of extension of said hanger arm from the cast concrete structure.
5. A furring hanger device adapted to be mounted in connection with a concrete casting form so as to be anchored in a concrete structure when poured thereinto, comprising a unitary member produced from a metallic strip of suitable width and thickness, comprising a foot-piece adapted to rest upon a form wall, an upwardly arched anchor-loop connected with the outer end of said foot-piece, a perforate hanger arm depending from the outer leg of said anchor-loop for external projection from the form, and a gauging stop lug struck out of said hanger arm inwardly thereof and adapted to engage the marginal portion of the form wall so as to both support said anchor-loop against displacement and predetermine the distance of extension of said hanger arm from the cast concrete structure.
6. A furring hanger device adapted to be mounted in connection with a concrete casting form so as to be anchored in a concrete structure when poured thereinto, comprising a unitary member produced from a metallic strip of suitable width and thickness, comprising a foot-piece adapted to rest upon a form wall, an upwardly arched anchor-loop connected with the outer end of said foot-piece, a perforate hanger arm depending from the outer leg of said anchor-loop for external projection from the form, a gauging stop lug struck out of said hanger arm inwardly thereof and adapted to engage the marginal portion of the form wall so as to both support said anchor-loop against displacement and predetermine the distance of extension of said hanger arm from the cast concrete structure,

and said foot-piece having a nail hole to receive a nail for fastening the device to the form wall.

7. A furring hanger device adapted to be mounted in connection with a concrete casting form so as to be anchored in a concrete structure when poured thereinto, comprising a unitary member produced from a metallic strip of suitable width and thickness, comprising a foot-piece adapted to rest upon a form wall, an upwardly arched anchor-loop connected with the outer end of said foot-piece, a perforate hanger arm depending from the outer leg of said anchor-loop for external projection from the form, a gauging stop lug struck out of said hanger arm inwardly thereof and adapted to engage the marginal portion of the form wall so as to both support said anchor-loop against displacement and predetermine the distance of extension of said hanger arm from the cast concrete structure, and said foot-piece having a nail hole to receive a nail for fastening the device to the form wall, said nail hole being laterally offset from a center line extending through said perforate hanger arm.

20 8. A device of the kind described, comprising an arched body, a perforate hanger arm depending from one end of said arched body, and a stop-lug extending inwardly from said hanger arm substantially in the plane of the base of said arched body.

9. A device of the kind described, comprising an upwardly arched body having a horizontal foot-piece extending from its inner leg, a perpendicular perforate hanger arm extending from the outer leg of said arched body, and a horizontal stop lug extending inwardly from said hanger arm to lie substantially in the plane of said foot-piece.

10. A device of the kind described, comprising an upwardly arched body having a horizontal foot-piece extending from its inner leg, a perpendicular perforate hanger arm extending from the outer leg of said arched body, a horizontal stop lug extending inwardly from said hanger arm to lie substantially in the plane of said foot-piece, said foot-piece having a nail hole to receive a nail for fastening the device to a form wall.

11. A device of the kind described, comprising an upwardly arched body having a horizontal foot-piece extending from its inner leg, a perpendicular perforate hanger arm extending from the outer leg of said arched body, a horizontal stop lug extending inwardly from said hanger arm to lie substantially in the plane of said foot-piece, said foot-piece having a nail hole to receive a nail for fastening the device to a form wall, said nail hole being laterally off-set from a center line extending through said perforate hanger arm.
